TOBACCO CUTTER

Goffredo Gamberini, Bologna, Italy, assignor to American Machine & Foundry Company, a corporation of New Jersey

Filed July 16, 1962, Ser. No. 210,075

7 Claims. (Cl. 146—119)

This application is a continuation-in-part of application Serial No. 830,834, filed July 31, 1959, now abandoned.

The present invention relates to a shredding machine for tobacco or the like, in which the tobacco leaves, coming from a suitable spout, are shredded by a rotating cutting head, provided with several blades which are substantially and preferably inclined or askew and which are continuously sharpened during the operation by a cylindrical grinding tool extending over their entire length or by a grinding tool of shorter length but moveable along its axis so as to affect the blades over their entire length, the blades protruding at the same time progressively and automatically from the head so as to compensate for their wear and to maintain their cutting edges always in an ideal cylindrical path of constant diameter which brushes by the spout.

During the operation of the shredder, the axis of rotation of the cutting head is therefore maintained in a fixed initially adjusted working position. It is possible, however, to shift the cutting head at will by a manual control away from and toward the tobacco outlet, in order to inspect the latter, or to adjust the cutting head with precision in relation to the outlet, for the initial setting of the cut.

The devices for shifting the cutting head relative to the tobacco outlet may be designed in a variety of ways. Preferably the cutting head is supported on a pivotable fork, hinged on a vertically moveable slide and articulated to the frame of the shredder by means of one or two braces in such a way that as the slide descends, the cutter head supporting fork is forced by the braces to pivot in an opposite direction to the spout, thereby moving the cutting head away therefrom, while as the slide rises, the reverse movement of the cutting head is automatically brought about. But when acting only on the braces which connect the cutter head supporting fork to the frame of the machine and for shifting the braces forward and back by means of an eccentric on their pins fastened to the frame and to which the braces are articulated, the cutting head supporting fork can be made to pivot in its raised working position, away from and toward the tobacco outlet, so as to permit the exact initial positioning of the cutting head in relation to said spout.

The device which during the operation of the shredder causes the automatic protrusion of the blades from the cutting head can likewise be designed in any manner suitable for the purpose. The blades are generally substantially flat and each of them is caused to advance or is pushed progressively out of the cutting head, preferably by a screw feed. Such blade-advancing devices derive their movement from the rotation of the cutting head, to which they are coupled by means of a suitable differential transmission. The blade-advancing mechanism preferably comprises means for varying the rate of forward movement of the blades, means for automatically stopping the shredder upon exhaustion of the blades (also when only one blade is exhausted or worn out, if the blades did not initially all have equal width) and means for the rapid handling of the blade-advancing elements for the replacement thereof and for their setting.

These and other characteristics of the invention will be evident from the following description of a preferred em-

2

bodiment illustrated by way of example in the annexed drawings, in which:

FIG. 1 illustrates schematically in lateral elevation, with parts broken away and parts in section, a tobacco shredder according to the invention;

FIG. 2 illustrates, on an enlarged scale, the rotating cutting head of the shredder in transverse section along line II—II of FIG. 4;

FIG. 3 illustrates, on a larger scale, a detail of the cutting head, in transverse section along line III—III of FIG. 4;

FIG. 4 is a longitudinal section, on a reduced scale, of the cutting head along line IV—IV of FIG. 2;

FIG. 5 shows a plan view, partly in section, of a detail of blade 5 and its securing means;

FIG. 6 shows a vertical view, partly in section, of the details of FIG. 5;

FIG. 7 shows details of the interconnection between the rotating head and the blade feed; and

FIG. 8 shows details of the interconnection between the two shafts which control the blade feed.

With reference to the figures, the illustrated shredder comprises two conveyor belts, a lower belt 1 and an upper belt 2, converging toward the spout 3. The tobacco leaves are charged on the lower belt 1, and are pushed by it toward the spout 3, while being progressively compressed between said belt 1, and the upper belt 2, in order finally to be expelled through spout 3. The tobacco emerging from spout 3, is shredded by a rotating cutting head 4, which is arranged in front of spout 3, and which carries a plurality of inclined blades 5, disposed at regular angular intervals and extending over the entire width of the spout 3. The outer cutting edges of the blades 5, lie on the surface of an ideal cylinder 6, which, in the working position of the cutting head, skims the spout 3. The rotating cutting head 4 is driven by the motor (not illustrated) of the shredder over trapezoidal belts 39 and a pulley 40 installed on shaft 13 of the head 4.

During the operation of the shredder, the blades 5 of the cutting head are continuously sharpened by means of a cylindrical grinding tool 7, which extends over the entire length of the blades 5. This grinding tool 7, is supported on the cutting head 4, on the opposite side to spout 3, and is driven positively by a suitable motor (not shown), being swept by each blade 5, with each rotation of the cutting head 4. The cylindrical grinding tool 7, is mounted on a pivotable support 8, hinged at 9 to the frame 10, of the shredder, means being provided for adjusting and maintaining said support in a working position so that the grinding tool acts in the desired manner on the cutting edges of blade 5. The support 8 of grinding tool 7 can be made to pivot upward about its fulcrum 9, by a manually controlled screw 11, so as to lift the grinding tool and to bring it into contact with an overlying diamond reconditioning device 12, which is mounted to slide along the generatrix of the grinding tool stone in suitable guides and which serves to dress the grinding tool.

During the operation of the shredder, the shaft 13, of the rotating cutting head 4, is maintained in an initially preset fixed working position and to compensate for the consumption or wear of the blades caused by their being continuously sharpened by the grinding tool 7, the blades 5, automatically and progressively protrude from the cutting head 4, so as to maintain their outer cutting edges always on the ideal cylinder surface 6, and spaced from the spout 3. For this purpose the invention provides a special automatic device for the advance of the blades 5, which will be described below.

The cutting head 4, although held in fixed position during operation, can be shifted at will away from and toward the spout 3, by a greater or smaller amount and with man-

ual control, especially for the purpose of positioning the axis of the cutter head fixedly relative to the spout 3. To this end the cutting head 4, is mounted, in the illustrated example, on a pivotable support, for example, on a fork 14, hinged at 15 on a slide 16, which can slide vertically along column 18, under the action of a rack 76, a gear 78 on shaft 75, and a crank 79. The pivotable fork 14, is articulated to the frame 10 of the machine by means of two lateral braces 19, each hinged at 20 on the fork 14 and on an eccentric pin 21 on the frame 10, of the shredder. As the slide 16 descends along the vertical guides 17, the braces 19 cause fork 14 to pivot in an opposite direction to spout 3 and thus force the cutting head 4 to move away from spout 3. As slide 16 rises, the braces 19 cause the fork 14 to pivot toward spout 3, and thus advance the cutting head 4 to said spout. For the exact initial setting of the working position of the cutting head 4 in relation to spout 3, only the braces 19 are shifted by the action of an eccentric arrangement comprising a pin 21, an adjusting lug 72 secured through a pivot to the frame 10 of the shredder. The motion of the adjusting lug is limited by a set screw 74 which engages in an elongated slot in lug 72. In this way, the fork is slightly pivoted about its fulcrum 15 on slide 16 and the cutting head 4 is shifted a little away from and toward spout 3.

The blades 5, are flat and are kept in place on the corresponding inclined seats 22 of the cutting head 4, by means of superposed fastening plates 23 which are secured to the head 4 by means of stud bolts 24 (FIG. 3). Each blade 5 is lodged in a corresponding enclosure 123 of the fastening plate 23, means being provided in the form of calibrated washers 25 on the studs 24, as shown in FIG. 5, which cause these enclosures 123 to be slightly higher than the thickness of blade 5. Blade 5 can thus slide in transverse direction to the cutting head 4, in said enclosure 123 of the respective fastening plate 23 and on its own seat 22, while being firmly blocked on the cutting head 4 by a plurality of spring dowels 26 which frictionally engage with the blade. These spring dowels 26 are lodged in suitable seats in the cutting head 4, and are distributed in suitable manner over the length of blade 5. The cutting edge of each blade 5, protrudes slightly from the rotating head 4, by an amount required to obtain the exact cutting of the tobacco.

The automatic and progressive advance of each of the blades 5, during the operation of the shredder is effected in the example illustrated in FIG. 2 by means of two blocks 27, which are distributed over the length of the blade 5, one to the right and the other to the left of the transverse median plane of the cutting head 4, and which act on the inner rear edge of the blade. Blocks 27, to one side of the median plane are shown in section in FIG. 2, the blocks on the other side of the plane may be in the same position. Each of these blocks 27 slides transversely to the blade 5 (but is not pivotable) in a suitable guideway 30, in the cutting head 4 and is screwed onto a screw 28 which extends transversely to blade 5 below the same and is mounted rotatably (but not slidably) in suitable bearings 29 in head 4. Thus, when turning both screws 28, simultaneously and by the same amount, the respective blocks 27, engaging with these screws are made to advance in their guideways 30, pushing the respective blades 5 forward and causing these to protrude from the cutting head 4.

The screws 28, for advancing the blades 5, can also be operated singly and by hand, under the conditions and for the purposes stated below, by means of knobs 31, which are fastened externally on the rear ends of the screws 28 (FIG. 2 and FIG. 3). However, during the operation of the shredder all screws 28 for advancing the blades 5, are actuated simultaneously and automatically at the same speed by a common control device. This device comprises a shaft 32 coaxial with the cutting head 4 and mounted pivotably therein. On this shaft 32, in a cavity 104, of the cutting head 4, two endless screws 33 are keyed, one

for each group, right and left, of the blade-pushing blocks 27. The cavity 104, as may be seen in FIG. 4, extends through much of the internal medial space of the rotating cutting head 4, except for a centrally positioned hub 70, integral with head 4, to lend rigidity to the structure. On each screw 28 for advancing the blades 5, there is keyed a gear 34, which meshes with a gear 35 axially slidable on a corresponding countershaft 36 parallel to the respective screw 28 and mounted pivotable in the cutting head 4. A spring 38 normally maintains the slidable gear 35 in engagement with the gear 34. On each countershaft 36 is mounted moreover a helicoidal gear 37, and all these helicoidal gears 37 belonging to the right and left groups of the advancing screws 28 mesh with the respective endless screw 33 of the center shaft 32. During operation of the shredder, the center shaft 32 for the control of the advance of the blades 5 is urged in a relative rotary movement with respect to the rotating cutting head 4 by means to be described below and causes the very slow continuous simultaneous advance of all blades 5, and at the same time all advancing screws 28 are made to rotate with the same instantaneous speed through respective helicoidal gear pairs 33, 37 and the cylindrical gear pairs 35, 34, thereby sliding forward all blade-pushing blocks 27.

Preferably, according to the invention, the movement of the shaft 32, which controls the advance of the blades 5 is derived from the rotation of the cutting head 4, so that the rate of advance of the blades 5 automatically depends on the speed of rotation of the cutting head and hence on the frequency with which the grinding tool 7 acts on the cutting edges of the blades 5. For this purpose, the shafts 113, 213, to which cutting head 4 is secured, are hollow. The shafts are mounted rotatably by means of roller bearings 41 in the pivotable support fork 14. Shaft 42 is prolonged axially on the left, as seen in FIG. 4, through one side of hollow shaft 113, coaxial therewith. It protrudes to the left of fork 14 coaxially with the cutting head 4. Shaft 42 is freely pivotable in the hollow shaft 113 of the cutting head 4 and is coupled to shaft 32 by means of a straight-tooth face coupling 43, as shown in FIG. 8, or by means of any other equivalent coupling or clutch capable of disengaging automatically when the two shafts 32, 42 are displaced reciprocally in axial direction away from each other. Shaft 32 is also slidably axially in the cutting head 4, extending into the opposite hollow shaft 213 thereof, and is urged axially toward shaft 42 by a spring 44 which normally maintains the coupling 43 engaged. It should be apparent, therefore, that the shaft which controls the advance of the blades 5 is formed of two coaxial half-shafts 32 and 42, coupled together by the coupling 43. In the following, the two half-shafts will be referred to as internal half-shaft 32 and external half-shaft 42.

Mounted on the outer end of the external half-shaft 42 and freely rotatable thereon is a gear 46. Gear 46 is secured for rotation to the cutting head 4, being coupled to shaft 113 of the cutting head by means of a claw coupling 146, shown in FIG. 4, but as best seen in FIG. 7. Near the left-hand end of the external half-shaft 42, to one side of the gear 46, a pulley 45 is loosely mounted. Opposing the left-hand face of gear 46, another coaxial gear 47 is integrally secured to half-shaft 42. Gear 47 has one more, or a few more, teeth than gear 46. Thus, for example, gear 47 may have 100 teeth, while 46 has 99. A satellite pinion 48, is carried by a housing 49 which is integral with the pulley 45, and rotates together with pulley 45 on the half-shaft 42. Satellite pinion 48 engages with both gears 46 and 47. Another pulley 50 is keyed to hollow shaft 113. Pulley 50 controls the advance of the blades 5 through a belt 51 which drives a pulley 52. Pulley 52 is keyed on a countershaft 53, keyed to which also is an expandable pulley 54. Pulley 54 actuates another belt 55 which, in turn, drives box 49 which rotates satellite 48.

Under the above conditions, during the operation of the shredder, pulley 50, integral with the cutting head 4, rotates pulley 45, and the satellite-holding box 49 integral therewith, by means of the transmission train 50, 51, 52, 54, 55 and 45. The angular speeds of the cutting head 4 and of the pulley 45 differ by a certain amount determined by the ratio of the dimensions of the pulleys in the train. The same speed ratio exists between the angular speeds of the gear 46 directly coupled to the cutting head and the satellite-holding box 49, integral with the pulley 45. Consequently, the satellite 48 rotates about its own axis and transmits the difference in angular speed to the half-shaft 42 through gear 47, with a reduction corresponding to the ratio between the two gears 46 and 47. The relative speed thus obtained between the rotating cutting head 4, and the external half-shaft 42 is transmitted by the latter to the internal half-shaft 32 through coupling 43 and serves to produce the very slow advance of the blades 5 by means of the devices described before. The rate of advance of the blades 5 can be varied within certain limits by varying the effective diameter of the expandable pulley 54 which may be changed by tightening or separating the pulley halves by means of screws such as 54A.

The shredder according to the invention is provided moreover with a device which automatically stops the machine when even one of the blades 5, is worn out or in case of an overload. For that purpose, in the illustrated embodiment, the internal half-shaft 32 which controls the advance of the blades is arranged so that it is axially slidable and is coupled to the external half-shaft 42 by means of the face coupling 43 or a clutch, as shown in FIG. 8. Moreover, as shown in FIG. 4, the internal half-shaft 32 projects outward to the right of hollow shaft 213 and its free end is engageable with an adjustable screw 56 on a micro-switch 57 which forms a part of the electric control circuit of the shredder. A blade 5 is considered worn out when its reduction in size, due to wear, and sharpening by grinding tool 7, permits its respective blade-pushing blocks 27 to advance to their extreme forward positions and reach the front end of their guides 30 where they are stopped against their respective front supports 29, of their respective advancing screws 28 (FIG. 2). The blade-pushing blocks 27 then prevent further rotation of their screws 28 and hence also of their respective cylindrical gear pairs 34, 35, as well as the helicoidal wheels 37. Consequently, as the half-shaft 32 continues its rotation, the endless screws 33 keyed on said shaft and engaged in the helicoidal wheels 37, now blocked, impart to the half-shaft 32 an axial movement in the direction of the arrow in FIG. 4 and against the action of the return spring 44. The half-shaft 32, therefore, shifts slightly outward and by its end 56 actuates the micro-switch 57, opening it or closing it so as to cause the stopping of the shredder. If the micro-switch 57 did not function and the cutting head 4 continued to rotate, the half-shaft 32 would continue to shift in axial direction, in the same sense as mentioned above and still under the action of the endless screws 33, for a distance sufficient to cause the disengagement of the face coupling 43. In this way the internal half-shaft 32 is automatically uncoupled from the external shaft 42 and hence from its actuating mechanism, and the protrusion of the blades 5 is stopped while the rotation of the cutting head 4 continues. As soon as the latter is stopped, spring 44 shifts the half-shaft 32 axially to the left, until it again engages coupling 43 and restores conditions to normal.

The invention also comprises a device which permits manual actuation of screws 28, singly or by pairs, for the advance of any of blades 5, or for the purpose of bringing blade-pushing blocks 27 rapidly back to their starting position after exhaustion of the respective blade, or to effect any manipulation necessary for the adjustment of any blade, such for example, as regulating its correct initial projection from the cutting head 4. Every screw

28, can be rotated by hand by means of its external knob 31, but for that purpose, it is necessary first to loosen its respective screw 28 from its irreversible actuating helicoidal couple 33, 37. Therefore, there is provided for each blade 5, in the cutting head 4 a bar or plate element 58 (FIGS. 2 and 4) which cooperates with all sliding gears 35 coupled to the advancing screws 28, and which is disposed on the side of these gears 35, opposite their return springs 38. Bar 58, can be shifted parallel to the shafts 36 of the sliding gears 35, by means of any manually controlled device, so as to push all gears 35 axially on their shafts 36, counter to the action of the springs 38, until gears 35 disengage from gears 34 fastened on the blade-advancing screws 28. In this way, each screw 28 may be freed and may be manipulated by its respective knob 31. Upon completing the manipulation, bar 58 is returned to the starting position, and the springs 38 push sliding gears 35 back to re-engage with gears 34.

In the embodiment illustrated, the device for the 20 placement and manipulation of bar 58, consists of a ferrule 59 (FIGS. 3 and 4) on which bar 58 is fastened transversely and which slides on a fixed shaft 60, parallel to the shafts 36 of the sliding gears 35 and disposed midway between shafts 36. Ferrule 59 is shifted axially on its own shaft 60, by means of an eccentric 61 which is fastened to a pin 62 projecting to the outside through plate 23 for the attachment of the blade and is pivotable by hand by means of a key. The ferrule is provided with a transverse slot in which a pin extending from eccentric 61 engages. When the eccentric is rotated in either direction, the pin pushes the ferrule along shaft 60 in a respective direction.

Obviously, the invention is not limited to the embodiments just described and illustrated, but may be widely 35 varied and modified, especially structurally, without thereby departing from the spirit of the invention set forth above and claimed in the following.

What is claimed is:

1. In a shredding machine for cutting leaf tobacco, 40 in combination, a machine frame, a rotatable cutter head, a first and a second hollow shaft on which said head is mounted, means for rotatably supporting said hollow shafts about a fixed axis relative to said frame, knife means slidably mounted in said cutter head, a two-piece shaft mounted for axial rotation in said hollow shafts, gearing operatively connecting said knife means and said two-piece shaft for advancing said knife means outwardly of said head at a predetermined rate during the operation of the machine, a variable speed reduction drive 45 operatively connecting said cutter head and said two-piece shaft, said drive comprising a gear housing rotatable about said two-piece shaft, a drive gear in said housing secured to said first hollow shaft, a driven gear secured to one piece of said two-piece shaft, a pinion in said housing, operatively engaging said gears, pulley means 50 including an expandable pulley drivingly connecting said cutter head and the said gear housing, and means for discharging tobacco across the peripheral path of said cutter head.

2. A shredding machine for cutting leaf tobacco, comprising, in combination, a machine frame, a rotatable cutter head, means for rotatably supporting said cutter head about a fixed axis relative to said frame, knife means slidably mounted in said head, a feed mechanism in said cutter head for slidably projecting said knife means, a stationary stop to arrest said feed mechanism after a predetermined distance of feed, a drive for said feed mechanism including a drive member and a driven member 55 disengageably connected to each other, said driven member being movable to a disengaged position, means to bias said driven member into engaged operative position while driving a predetermined feed load, said biasing means yielding when said load exceeds said predetermined feed load, said driven member then moving to a disengaged position incapacitating said drive, whereby said

60 3. A shredding machine for cutting leaf tobacco, comprising, in combination, a machine frame, a rotatable cutter head, means for rotatably supporting said cutter head about a fixed axis relative to said frame, knife means slidably mounted in said head, a feed mechanism in said cutter head for slidably projecting said knife means, a stationary stop to arrest said feed mechanism after a predetermined distance of feed, a drive for said feed mechanism including a drive member and a driven member 65 disengageably connected to each other, said driven member being movable to a disengaged position, means to bias said driven member into engaged operative position while driving a predetermined feed load, said biasing means yielding when said load exceeds said predetermined feed load, said driven member then moving to a disengaged position incapacitating said drive, whereby said

70 4. A shredding machine for cutting leaf tobacco, comprising, in combination, a machine frame, a rotatable cutter head, means for rotatably supporting said cutter head about a fixed axis relative to said frame, knife means slidably mounted in said head, a feed mechanism in said cutter head for slidably projecting said knife means, a stationary stop to arrest said feed mechanism after a predetermined distance of feed, a drive for said feed mechanism including a drive member and a driven member 75 disengageably connected to each other, said driven member being movable to a disengaged position, means to bias said driven member into engaged operative position while driving a predetermined feed load, said biasing means yielding when said load exceeds said predetermined feed load, said driven member then moving to a disengaged position incapacitating said drive, whereby said

drive is arrested upon said knife means jamming or contacting said stop.

3. A shredding machine for cutting leaf tobacco, comprising, in combination, a machine frame, a rotatable cutter head, means for rotatably supporting said cutter head about a fixed axis relative to said frame, knife means slidably mounted in said head, a feed drive in said cutter head to slidably project a said knife means therefrom, said feed drive including a mechanism, said mechanism including a drive member, a driven member, and a gear train to project said knife, said gear train including a worm gear secured on said driven member, means for normally biasing said driven member into driving engagement with said drive member and said driven member being displaceable axially against said biasing means from and out of said driving engagement, said worm gear moving said driven member axially upon arrest of said feed drive, a stop to arrest said knife feed after a predetermined amount of feed, said driven member then moved by said worm gear against said biasing means to a disengaged position incapacitating said drive, whereby said drive is arrested upon said knife feed jamming or contacting said stop.

4. A shredding machine for cutting leaf tobacco, comprising, in combination, a machine frame, a rotatable cutter head, means for rotatably supporting said cutter head about a fixed axis relative to said frame, knife means slidably mounted in said head, a feed drive in said cutter head to slidably project said knife means therefrom, said feed drive including a mechanism, said mechanism including a drive member, a driven member, and a gear train to project said knife, means for normally biasing said driven member into driving engagement with said drive member and said driven member being displaceable axially against said biasing means from and out of said driving engagement, an instrumentality actuated by said gear train for moving said driven member axially upon arrest of said feed drive, a stop to arrest said knife feed after a predetermined amount of feed, said driven member then moved by said instrumentality against said biasing means to a disengaged position incapacitating said drive, whereby said drive is arrested upon said knife feed jamming or contacting said stop.

5. A shredding machine for cutting leaf tobacco, comprising, in combination, a machine frame, a rotatable cutter head, means for rotatably supporting said cutter head about a fixed axis relative to said frame, knife means slidably mounted in said head, a feed mechanism in said head for slidably projecting said knife means therefrom, said feed including a mechanism, said mechanism including a drive member and a driven member disengageably connected to each other, said driven member being provided with an endless screw engaging with a helicoidal

5 gear, said driven member being movable to a disengaged position, means to bias said driven member into engaged operative position while driving a predetermined feed load, said biasing means yielding when said load exceeds said predetermined feed load, said driven member then moving to a disengaged position incapacitating said drive, whereby said drive is arrested upon jamming or contacting said stop.

10 6. A shredding machine for cutting leaf tobacco, comprising, in combination, a machine frame, a rotatable cutter head, means for rotatably supporting said cutter head about a fixed axis relative to said frame, knife means slidably mounted in said head, a feed mechanism in said cutter head for slidably projecting said knife means, a stationary stop to arrest said feed mechanism after a predetermined distance of feed, a drive for said feed mechanism including a drive member and a driven member disengageably connected one to another, said driven member displaceable axially away from said drive member, said driven member being movable to a disengaged position, means to bias said driven member into engaged operative position while driving a predetermined feed load, said biasing means yielding when said load exceeds said predetermined feed load, said driven member then moving to a disengaged position incapacitating said drive, whereby said drive is arrested upon jamming or contacting said stop.

15 7. A shredding machine for cutting leaf tobacco, comprising, in combination, a machine frame, a rotatable cutter head, means for rotatably supporting said cutter head about a fixed axis relative to said frame, knife means slidably mounted in said head, a feed mechanism in said cutter head for slidably projecting said knife means, a stationary stop to arrest said feed mechanism after a predetermined distance of feed, a slip clutch, a drive for said feed mechanism including a drive member and a driven member disengageably connected by said slip clutch, said slip clutch disengaging said members upon actuation, means to actuate said clutch to a disengaged position upon a predetermined feed load value, biasing means normally engage said clutch yielding when said load reaches said predetermined value, said biasing means then actuating said clutch to incapacitate said drive, whereby said drive is arrested upon said knife means jamming or contacting said stop.
